UNITED STATES PATENT OFFICE

GUSTAVE M. FAUSER, OF ARDSLEY ON HUDSON, NEW YORK

DESIGN FOR A PRINTED FLOOR COVERING

Application filed August 23, 1932. Serial No. 44,668. Term of patent 7 years.

To all whom it may concern:

Be it known that I, GUSTAVE M. FAUSER, a citizen of the United States, residing at Ardsley on Hudson, in the county of Westchester and State of New York, have invented a certain new, original, and ornamental Design for Printed Floor Covering, of which the following is a specification, reference being had to the accompanying drawing, forming a part hereof.

The drawing represents a plan view of a section of printed floor covering showing my

new design, a unit of the design being illustrated in the area bounded by the dot and dash lines A—A', B—B', C—C', and D—D', said unit being repeated continuously in the manner indicated, throughout the area of the floor covering.

I claim:

The ornamental design for printed floor covering, substantially as shown and described.

In testimony whereof, I affix my signature.
GUSTAVE M. FAUSER.
